[57] CLAIM

The ornamental design for an electronic calculator, substantially as shown.

DESCRIPTION

FIG. 1 is a front elevational view of a electronic calculator showing my new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a perspective view thereof;

FIG. 8 is a perspective view thereof with front cover opened;

FIG. 9 is a front elevational view thereof with front cover opened;

FIG. 10 is a top plan view thereof with front cover opened; and

FIG. 11 is a right side elevational view thereof with front cover opened.
